UNITED STATES PATENT OFFICE.

CHARLES JENKS AND CHRIS E. NELSON, OF DARLINGTON, WISCONSIN.

HOISTING DEVICE.

Application filed June 2, 1924. Serial No. 717,399.

To all whom it may concern:

Be it known that we, CHARLES JENKS and CHRIS E. NELSON, citizens of the United States, residing at Darlington, in the county 5 of Lafayette and State of Wisconsin, have invented new and useful Improvements in Hoisting Devices, of which the following is a specification.

This invention relates to hoisting devices, 10 and contemplates a structure primarily intended to facilitate the handling of hogs on a farm when butchering.

More specifically stated, the invention 15 contemplates the provision of a device adapted to be pivotally mounted upon the door frame of a barn or the like, and constructed to raise and support a hog suspended therefrom, outside the barn to allow the hog to cool after having been dressed, and 20 subsequently swung within the barn with the minimum of time and effort.

The nature and advantages of the invention will be better understood when the following detailed description is read in connection with the accompanying drawings, 25 the invention residing in the construction, combination and arrangement of parts as claimed.

In the drawings forming part of this application, like numerals of reference indicate similar parts in the several views, and wherein:

Figure 1 is a side elevation of the device showing how it is mounted upon the door 35 frame of a building.

Figure 2 is a sectional view taken on line 2-2 of Figure 1.

Figure 3 is a sectional view taken on line 3-3 of Figure 1.

Figure 4 is a detail sectional view through 40 the connection between the arm and bracing elements.

The device forming the subject matter 45 of this invention essentially includes a post or upright 10 which is adapted to be arranged within the door frame of a building, and mounted for rotation, so that the supporting and raising device can be swung either to a position outside the building or inside the building as the occasion may require. For this purpose the upright 10 is provided with trunnions 11 and 12 respectively, the former being journaled in the top of the door frame as clearly 50 shown in Figure 1, while the latter is journaled in the horizontally disposed

branch 13 of the substantially L-shaped bracket 14 which is secured to one side of the door frame in any suitable manner. Projecting at a right angle from the upper end of the standard or upright 10 is a supporting arm 15 which is suitably braced by diagonally arranged bracing elements 16 having their upper extremities secured to the opposite sides of the supporting arm 15 as shown in Figure 4, while the lower ends of these bracing elements are secured in any suitable manner to the base plate 17 utilized to support the raising and lowering mechanism upon the upright or standard 10.

The plate 17 is arranged against the standard 10 and has one side recessed as at 18 to conform to the curvature of the upright 10 as clearly shown in Figure 2. The plate 17 is held fixed to the upright 10 by means of U-shaped clamps 19 which straddle the upright 10, and have their extremities passed through openings in the plate 17 as clearly illustrated. Bolted on the plate 17 is the attaching base portion 20 of a suitable bracket including spaced parallel portions 21, which portions terminate to provide spaced pairs of bearings 22 and 23 respectively. Journaled between the bearings 22 is a drum 24 to which a hoisting cable 25 is terminally secured, and adapted to be wound about and unwound from the drum. This cable 25 is trained over idle pulleys 26 suspended from the supporting arm 15, and is then formed to provide a loop 27, the free end of which is secured to the outer end of the supporting arm 15 as at 28. This loop supports the movable sheave block in the ordinary well known manner. Keyed upon the shaft 30 with the same key 31 employed to hold the drum 24 thereon, is a gear 32, which meshes with a small gear 33 keyed upon a stub shaft 34, which latter shaft is equipped with a handle 35. The shaft 34 is journaled in the bearing 23 above referred to. Manifestly by turning the handle 35 in one direction the cable is wound about the drum 24, thereby elevating the movable sheave 29, and when the handle is rotated in an opposite direction, the cable is unwound from the drum 24 and the movable sheave lowered. The structure is particularly advantageous 100 for the use above outlined, in that a hog can be easily and conveniently raised to an elevated position and suspended from

the sheave block outside the barn or building, and allowed to cool after having been dressed. Pivoted on one of the parallel portions 21 of the bracket above referred to is a pawl 36 which can be conveniently swung into active engagement with the gear 32, to prevent retrograde movement of the drum and thus hold the sheave block 29 at any desired height. After the hog 10 has been cooled, the entire supporting structure can be easily and conveniently swung through the door opening to the inside of the building, this being permitted by the fact that the upright or post 10 is mounted 15 for rotation within the door frame as shown in Figure 1.

While it is believed that from the foregoing description, the nature and advantages of the invention will be readily apparent, we desire to have it understood that we do not limit ourselves to what is herein

shown and described and that such changes may be resorted to when desired as fall within the scope of what is claimed.

What we claim is:

Means for supporting the crane on the door frame of a building, said means comprising a bracket secured to the door frame, a post journalled between the bracket and the upper part of said frame, a plate having a concaved portion at one side to accommodate itself and said post, U-shaped clamps embracing the posts and passed through said plate for holding the latter attached to the post, and said plate also including an operating mechanism for the crane as and for the purpose specified.

In testimony whereof we affix our signature:

CHARLES JENKS.
CHRIS E. NELSON.
